NURSING NIPPLE FOR USE WITH A NURSING BOTTLE

Michael C. Ritsi, 7950 SW. 16th St., Miami, Fla. 33155

Filed Mar. 23, 1970, Ser. No. 22,029

Term of patent 14 years

The portion of the term of the patent subsequent to
May 13, 1983, has been disclaimed

Int. Cl. D24—05
U.S. Cl. D83—8

FIG. 1 is an elevation view of a nursing nipple for use with a nursing bottle showing my new design;

FIG. 2 is a top plan view;

FIG. 3 is a bottom plan view; and

FIG. 4 is a view in cross section of the nipple taken on line 4—4 of FIG. 1.

I claim:

The ornamental design for a nursing nipple for use with a nursing bottle, as shown and described.
